UNITED STATES PATENT OFFICE.

WILLIAM LEON, OF NIAGARA FALLS, NEW YORK.

KEYLESS LOCK.

1,403,256.

Specification of Letters Patent. Patented Jan. 10, 1923.

Application filed February 3, 1921. Serial No. 442,063.

To all whom it may concern:

Be it known that I, WILLIAM LEON, a citizen of the United States, residing at Niagara Falls, in the county of Niagara and State of New York, have invented certain new and useful Improvements in Keyless Locks, of which the following is a specification.

My invention relates to keyless lock, and more particularly to locks for doors, trunks, chests, etc.

One of the objects of my invention is to provide a lock which can be easily and conveniently manipulated without the use of a key and wherein provision is made for actuating the same from either side of a door.

Another object of my invention is the provision of a keyless lock of this type which embodies a principle permitting the use of permutation mechanism comprising a single series of tumblers or a plurality of series and in which provision is also made for readily changing the concerted order of the tumblers so that a different adjustment or manipulation of one or more of the tumblers of the series, or each of the series, will be required to operate the lock.

A further object of my invention is the provision of a simple, inexpensive and durable device of this kind which is self-contained and readily insertable or removable from a door or other object and in which the principle involved can be readily embodied in various modifications.

With these and other objects in view to appear hereinafter, the invention consists in the novel features of construction, and in the arrangement and combination of parts to be hereinafter described and more particularly pointed out in the subjoined claim.

In the drawings:

Fig. 1 is a perspective view of a portion of a door showing one form of my invention applied thereto.

Fig. 2 is a vertical section through the door and co-operating door jamb showing my improved keyless lock in sectional elevation.

Fig. 3 is a detached perspective view of a portion of the lock plate and one of the slotted sleeves carried thereby forming part of a telescopic rod.

Fig. 4 is a detached perspective view of a portion of the lock frame with one of the supporting rods detachably secured thereto,

said rod also forming part of the telescopic rod.

Fig. 5 is an enlarged vertical section taken on line 5—5, Fig. 2.

Fig. 6 is an enlarged horizontal section taken on line 6—6, Fig. 2, the door jamb being omitted.

Fig. 7 is a horizontal section similar to Fig. 6 with a portion of the door and lock mechanism broken away and the operating parts in different positions.

Fig. 8 is a detached perspective view of one of the outer tumbler members.

Fig. 9 is a detached perspective view of one of the inner tumbler members.

Fig. 10 is a sectional elevation showing a modified form of lock applied to a chest.

Reference being had to the drawings in detail, like numerals refer to like parts throughout the several figures.

The numeral 11 designates a door, 12 a door jamb having a bolt-receiving pocket 13 and a bolt or latch plate 14 secured thereto, said bolt or latch plate being provided with the usual opening which registers with the pocket 13 so as to allow the bolt of the lock to pass through said opening and enter said pocket. The door is mortised from its edge, as at 15, and at one or both sides thereof, as may be desired, it is provided with an opening or openings 16 formed through one or both side walls of the mortise 15.

In the drawings I have shown a lock which can be manipulated from both sides of the door and consequently both side walls of the mortise are provided with the openings 16, but it will be apparent that in a lock adapted to be manipulated from one side of the door only, the opening 16 is formed in one side wall only of said mortise.

The lock comprises a lock plate 17 which is secured to the edge of the door in a manner to close the front end of the mortise 15, and this plate is provided with a bolt opening 18 and with two inwardly-projecting sleeve-like members 19 provided with transverse slots 20 along diametrically opposite lines, the slots being arranged in two longitudinal series with the slots of one series registering with those of the other.

21 designates a frame which is preferably L-shaped with one arm 22 thereof disposed horizontally and preferably in slidable contact with the upper wall of the mortise and 110

- its other arm 23 disposed vertically. Said frame has a lock-bolt 24 secured thereto which extends outwardly therefrom and the outer end of which is guided for movement 5 in the bolt opening 18 of the lock plate 17. Detachably secured to the vertical arm of the said lock frame are two supporting spindles or rods 25, each of which is entered in one of the sleeve members 19, and each 10 having a series of pins 26 extending therethrough and projecting therefrom at diametrically opposite points. The opposite ends of said pins extend through the slots 20 at opposite sides of the sleeves 19 and project 15 a distance outwardly beyond the surface of said sleeves. The supporting spindles or rods 25 are preferably reduced at their inner ends to provide a shoulder which bears against the vertical arm of the lock frame, 20 the reduced portion thereof extending through said arm and having a retainer pin 27 passed therethrough so as to securely hold said spindle on said frame and prevent longitudinal movement thereof.
- 25 The lock plate 17 and vertical arm 23 of the frame 21 may, in a broad sense, be termed supporting elements or members since they support the sleeve-like members 19 and the supporting spindles or rods 25, and said 30 sleeve-like members and supporting spindles or rods may be termed telescopic rods, since said spindles or rods are adapted to slide with said sleeve-like members.
- 35 In the drawings I have shown four pairs of slots 20 in each sleeve-like member 19, each pair being comprised of opposite registering slots, and four pins 26 in each supporting spindle or rod 25, but these may be diminished or increased in number, as may 40 be desired.
- 45 Surrounding each sleeve-like or outer rod member 19 are four inner tumbler members 28, each of which is provided with a bore 29 of a size to permit free rotation of said outer rod member, each tumbler member being counterbored, as at 30, to form an annular pin-way or groove and from said pin-way or groove a longitudinal groove 31 extends, which at times will receive the projecting 50 ends of the pins 26, as will be hereinafter described. By counterboring the inner tumbler member, forwardly-facing shoulders 32 are formed therein.
- 55 Each of the inner tumbler members is also provided with an external longitudinal projection or rig 33 serving as a key, and being preferably V-shaped. Surrounding each of the inner tumbler members 28 an outer tumbler member 34, which is provided with a 60 circular series of internal longitudinal V-shaped notches 35 serving as key ways. On the outer periphery of said outer tumbler member a circular series of letters, figures, or other characters 36 are formed, one letter 65 or other character being provided for each key-way. The longitudinal key formed on each of the inner members is adapted to be entered in any one of the key-ways 35 formed in the outer tumbler member.
- 70 In the preferred form, the diameter of the outer tumbler is somewhat greater than the thickness of the door so that with the lock positioned centrally in the door, or more particularly, with the telescopic rods positioned centrally within the mortise of the door, the outer tumbler members project beyond opposite faces of the door.
- 75 The openings 16 formed in the door are closed by plates 37, which may be fastened to the door in any suitable manner, preferably so that the outer plate can be removed only when or after removing the inner plate, as and in the manner commonly provided for in the better class of out-door locks of usual construction now commonly employed.
- 80 Each plate 37 has two slots 38 formed therein through which the outer tumbler members 34 can be manipulated, each plate having indicating or guide marks 39 with 90 which predetermined characters on the outer tumbler members are adapted to be aligned so as to position the lock mechanism to permit opening of the door. The lock bolt 24 is provided with a longitudinal opening 40, 95 one longitudinal wall of which is provided with a series of gear teeth 41. Passing through the door and the plates 37 and projecting outwardly a distance from both plates is an operating spindle 42 having 100 knobs 43 secured to opposite ends. At a point midlength, this spindle is provided peripherally with teeth 44 which are in mesh with the gear teeth 41 in the slot 40 and by means of which the lock frame and 105 the inner members of the telescopic ends secured thereto can be moved outwardly and inwardly.
- 110 With the parts in the position shown in Fig. 2, the lock bolt 24 is projected outwardly through the opening 18 in the lock plate 17 and extends into the pocket 13 in the door jamb, the tumblers being positioned to prevent rotation of the operating spindle 42. With the tumblers so positioned, the inner members 25 are moved forwardly in the outer members 19 of the telescopic rods with the pins 26 of said inner members engaging the front ends of the 115 slots 20, said pins projecting into the annular grooves or key ways 30, as clearly shown in Fig. 6. With the projecting ends of each pin thus arranged the inner members of the telescopic rods are held against forward movement by the inner end of the tumbler member directly in advance and against rearward movement by the shoulder 32 of the inner tumbler member with which it directly coacts.
- 120 With the pins projecting within the pin 130

ways 30 of the several tumblers, said tumblers are free to be rotated, but before it is possible to withdraw the lock latch 24 from the pocket 13 in the door jamb, it will be 5 necessary that the longitudinal grooves 31 in the inner tumbler members be brought into alinement with the projecting ends of the pins 26, and to accomplish this, the operator must know the exact character of 10 each tumbler which must be brought into alinement with the indicating or guide marks 39 on the outer or inner plate 37. When the tumblers are rotated so that all longitudinal grooves 31 therein are alined 15 with the pins 26, the knobs 43 are free to rotate, and upon rotating said knobs, the operating spindle 42 to which they are secured will cause the lock bolt to be moved inwardly, which bolt being secured to the 20 frame 21 will cause the inner members of the telescopic rods to move inwardly and the pins to enter the longitudinal grooves 31 in the inner tumbler members, as clearly shown in Fig. 7. With the parts in the positions last described, rotation of the tumbler members is prevented, and the door is 25 free to be opened or closed.

It is, of course, to be understood that any suitable spring or other catch device may 30 be used in connection with this improved lock, either as a separate unit, or as a part of this locking mechanism. It is also apparent that this locking mechanism can be arranged so that the tumblers are accessible 35 from one side of the door only, and that any catch device employed can be operated from both sides of the door, so that the door may be held closed, although not locked. Moreover, in the event of the tumblers being ac- 40 cessible from one side of the door only, a key lock may be employed at the other side of the door in addition to this improved locking mechanism.

Whenever it is desired to change the combination, it is simply necessary to remove one or more of the outer tumbler members and place the key of the co-acting inner tumbler member or members into a different key way or key ways in the outer tumbler members. 45 Thus, if the letters B, F, L and P on the upper series of tumblers, and the letters F, L, O and P on the lower series of tumblers were selected to serve as a combination which would assure operation of the lock bolt upon 50 rotating the knob, a change of position of a single outer tumbler in either the upper or lower series would necessitate the use of a change in the combination of letters, before it would be possible to manipulate the lock- 55 ing mechanism. Therefore, the combination of one series of tumblers could be changed and the combination of letters on the other series of tumblers left intact; or if desired, both series can be changed so that if a com- 60 bination which is being used to open the door member with said lock plate and comprising

becomes known to others, it will be found a simple matter to change the combination to any degree desired, even to include an entirely new set of letters or characters.

In Fig. 10, 45 designates a trunk or chest 70 having a cover 46, the cover being mortised, as at 15' and having a frame 21' provided with a slide bolt 24' at the inner end of the frame. In this modification the lock plate 17' is provided with an inwardly extending 75 arm 47 to which the outer member 19' of the telescopic rod is secured. To the frame, above the slide bolt 24', the inner member 25' of said rod is secured, and surrounding 80 said outer member are shown tumbler members 33' of the permutation mechanism. This mechanism, which includes outer and inner tumbler members and the outer and inner members 19' and 25', respectively, of the telescopic rod, is identical with the per- 85 mutation mechanism illustrated in the preceding figures of the drawings.

The trunk or chest 45 is provided with a pocket 13', and closing said pocket is a latch plate 14' having one or more openings 48. 90 The lock bolt 24' is provided at its lower edge with one or more hook-shaped projections 49, which are adapted to pass through the openings 18' in the lock plate 17' and through the openings 48 in the latch plate, 95 which latter openings register with the openings 18' in said lock plate. When the frame 21' is moved to the right hand end of the mortise 15', as shown in Fig. 10, the tumblers and projecting ends of the pins of the per- 100 mutation mechanism will be in positions corresponding to those shown in Fig. 6, so that the toothed portion of the spindle 41' can- not be rotated to actuate the slide bolt 24'. It is, of course, to be understood that the 105 tumblers will be accessible from the exterior of the cover in a manner similar to that shown in Fig. 1, and that when manipulat- 110 ing the tumblers and the proper combination of characters thereon are brought into con- 115 cert and in line with some indicating or guide mark on the cover 46, the lock can be actuated, or in other words, moved toward the left, and when so moved the hook ends of the projections 49 can be withdrawn through the openings 48 in the latch plate 14'.

The sleeve-like outer member 19 of each tele- 120 scoping-rod may also be considered as a hous- ing for a portion of the inner member, or the supporting spindle or rod 25, as more specifi- cally termed.

Having thus described my invention, what I claim is:

The combination with a door having a mortise therein, of a keyless lock entered in 125 said mortise and comprising a lock plate closing the outer end of said mortise, a sup- porting member spaced from said lock plate, a telescopic rod connecting said supporting 130 member with said lock plate and comprising

an outer sleeve-like member having a plurality of longitudinally disposed slots therein and an inner member having pins projecting therefrom and extending outwardly 5 through said slots, a lock bolt on said supporting member guided in said lock plate and having a longitudinal slot therein provided with gear teeth in one of its walls, and tumblers surrounding said sleeve-like outer 10 member, each tumbler having an internal an-

nular groove and a longitudinal groove opening into said annular groove, said pins projecting into said annular groove when said lock bolt is in locking position and into said longitudinal grooves when said lock bolt is in 15 unlocked position, and a spindle provided circumferentially with teeth meshing with the teeth in said slot.

In testimony whereof I affix my signature.
WILLIAM LEON.
